UNITED STATES PATENT OFFICE

166,693

CHILD'S BICYCLE

Walter Lines, Leigh Place, Godstone, Surrey, England, assignor to Lines Bros. Limited, Merton, London, England, a British company

Application September 5, 1951, Serial No. 16,518
In Great Britain April 30, 1951

Term of patent 14 years

(Cl. D34—15)

To all whom it may concern:

Be it known that I, Walter Lines, a subject of the King of Great Britain, residing at Leigh Place, Godstone, Surrey, England, have invented a new, original, and ornamental Design for a Child's Bicycle, of which the following is a specification, reference being made to the accompanying drawings, forming a part thereof.

In these drawings:

Fig. 1 is a side perspective view of a child's bicycle, showing my new design, the opposite side being substantially similar;

Fig. 2 is a side elevational view; and

Fig. 3 is a rear perspective view.

I claim:

The ornamental design for a child's bicycle, substantially as shown and described.

WALTER LINES.
